CLAIM

The ornamental design for a polygonal susceptor tray, as shown and described.

DESCRIPTION

FIG. 1 is a perspective view of a polygonal susceptor tray showing the new design;

FIG. 2 is a top plan view thereof;

FIG. 3 is a side elevational view thereof, the opposite side elevational view being the same as FIG. 3;

FIG. 4 is a bottom plan view thereof;

FIG. 5 is a longitudinal sectional view along the line 5—5 of FIG. 2;

FIG. 6 is a perspective view of a second embodiment of the polygonal susceptor tray;

FIG. 7 is a top plan view thereof;

FIG. 8 is a side elevational view thereof, the opposite side elevational view being the same as FIG. 8;

FIG. 9 is a bottom plan view thereof; and,

FIG. 10 is a longitudinal sectional view along the line 10—10 of FIG. 7.

The broken line showing of other portions of the polygonal susceptor tray is included for illustration only and forms no part of the claimed design.
